(57) **CLAIM**

The ornamental design for an archery bow riser weight as shown and described.

DESCRIPTION

FIG. 1 is a front-left angled view of the archery bow riser weight, showing the new design.

FIG. 2 is a front-left angled view thereof, showing the device attached to an archery bow.

FIG. 3 is a front view thereof.

FIG. 4 is a back view thereof.

FIG. 5 is a top view thereof.

FIG. 6 is a bottom view thereof.

FIG. 7 is a left-side view thereof; and,

FIG. 8 is a right-side view thereof.

The broken lines in the Figures depict environmental structure or unclaimed portions of the device and are for illustrative purposes only. The broken lines form no part of the claimed design.
